UNITED STATES PATENT OFFICE.

JOHN E. FEAGANS, OF DRESDEN, OHIO.

RAILROAD-TIE TRUSS.

Application filed October 26, 1926. Serial No. 144,342.

This invention relates to railway tracks and more particularly to a truss adapted to be applied to ties supporting the end portions of joined rail sections.

5 At the present time it is customary to connect the abutting ends of rails by means of a rail chair which is secured upon a tie. The joined ends of the rails are the weakest portions of a track and as a train passes over them its weight tends to force the joined rail ends and the tie supporting them downwardly and form a depressed place in the track with the resulting danger of a wreck.

10 Therefore, one object of the invention is to provide a truss which may be applied to the rail supporting ties and very firmly brace the tie upon which the joined ends of abutting rails rest against downward movement.

15 Another object of the invention is to permit the end portions of the truss to rest upon the upper face of adjacent ties and take the place of the usual tie plates used upon these ties.

20 Another object of the invention is to form the truss from a single strip of strong metal and thereby reduce the cost of manufacture.

The invention is illustrated in the accompanying drawings, wherein:

25 Figure 1 is a perspective view showing one of the improved trusses in operative relation to cooperating ties.

Figure 2 is a side elevation showing a fragment of a railway track with one of the trusses applied thereto.

30 Figure 3 is a top plan view of the structure shown in Figure 2.

The truss constituting the subject matter of this invention is preferably formed as a unitary structure and consists of a strip 35 of steel or other strong metal of suitable width and thickness, according to the weight of the rails with which it is to be employed.

The strip from which the truss is formed is bent adjacent its center to provide a flat intermediate portion 1 and also bent in spaced relation to its ends to provide end portions 2 which are connected with opposite ends of the intermediate portion 1 by arms or connecting portions 3. The arms 40

50 extend upwardly from the intermediate portion, as shown in Figure 2, and by referring to this figure it will be seen that they support the end portions 2 in a plane spaced above and substantially parallel to the plane 55 of the intermediate portion 1. Therefore, when the truss is in use the intermediate por-

tion 1 may extend transversely beneath the tie 4 upon which the joined ends of the rails 5 rest and the end portions 2 may rest upon the upper faces of the ties 6 spaced from 60 opposite sides of the tie 4. The thickness of the metal from which the truss is formed corresponds to the thickness of the tie plate 7 carried by the tie 4 and secured thereto by spikes 8 which engage opposite side portions 65 of the rail bases. The portions of the rails which rest upon the end portions 2 of the truss will, therefore, be retained at the proper elevation. It will thus be seen that the end portions 2 may serve as tie plates for 70 the ties 6. The end portions of the truss are of greater width than the bases of the rails and project from opposite sides thereof, as shown in Figure 3. Passages 9 which are preferably recesses leading from opposite 75 sides of the truss, are formed in the end portions 2 and are adapted to receive spikes 10 which serve to secure the rails 5 and also prevent movement of the truss relative to 80 the ties 6. It will thus be seen that the truss may be easily applied and, when in place, will very effectively brace the tie 4 and prevent it from having vertical movement which would permit dropping of the joined 85 ends of the rails. This prevents danger of a wreck as the joined rail ends are retained in the proper position and sagging or breaking of a joint prevented.

Having thus described the invention, what 90 I claim is:

1. A tie truss comprising a metallic strip bent adjacent its center and ends to provide intermediate and end tie engaging portions and other portions connecting the said end portions with opposite ends of the intermediate portion and supporting the end portions in a plane above the plane of the intermediate portion, the said end portions being adapted to be secured upon the upper faces of ties spaced from opposite sides of 95 a tie resting upon said intermediate portion and constituting tie plates upon which rails are to rest.

2. A tie truss comprising a metallic strip bent intermediate its length to provide an intermediate portion adapted to extend transversely across the under face of a tie supporting joined rail ends and arms diverging upwardly from the intermediate portion, said arms having their free end portions 100 bent to rest flat upon the upper faces of adjacent ties and extend longitudinally be- 110

neath the rails, the said end portions being of greater width than the rail bases and formed with apertures to receive spikes for engaging opposite side portions of the rail bases.

3. A tie truss comprising an elongated body having tie engaging intermediate and end portions, and other portions connecting the end portions with opposite ends of the intermediate portion, the said end portions being disposed in a plane spaced above and

substantially parallel to the plane of the intermediate portion and adapted to rest upon the upper faces of ties disposed at opposite sides of a tie resting upon the intermediate portion and constituting tie plates, said end portions being of greater width than the bases of rails to rest thereon and formed with passages to receive fasteners for engaging opposite sides of the rail bases. 15 20

In testimony whereof I affix my signature:
JOHN E. FEAGANS. [L. s.]
